UNITED STATES PATENT OFFICE.

GEORGE D. COLLAR, JR., OF GLENSIDE, PENNSYLVANIA, ASSIGNOR TO H. BRINTON CO., OF PHILADELPHIA, PENNSYLVANIA, A CORPORATION OF PENNSYLVANIA.

DIAL-ALIGNING DEVICE.

Application filed July 17, 1926. Serial No. 123,140.

My said invention relates to a dial aligning device such as is used in dial and cylinder knitting machines of the so-called "dogless" type, and it is an object of the same to provide a device of this character with means for obtaining a very accurate adjustment of the dial needles with reference to the cylinder needles by simple mechanism capable of maintaining such adjustment indefinitely for the reason that the parts exposed to wear are so arranged and have such large bearing surfaces that the device can be used over a very long period of time without such wear as would affect the adjustment and relative positions of the needles so as to necessitate re-adjustment.

Another object of the invention is to provide means in connection with the dial aligning device for ready and accurate adjustment of the dial in a vertical sense.

Referring to the drawings, in which similar reference characters indicate similar parts, and which drawings are made a part hereof:

Fig. 1 is an elevation of a part of a dial and cylinder knitting machine, with parts broken away for clearness of disclosure,

Fig. 2, a section on line 2—2 of Fig. 1,
Fig. 3, a section on line 3—3 of Fig. 1,

Fig. 4, a perspective of a part shown in Figs. 1 and 3,

Fig. 5, a detail of parts shown in Fig. 1,
Fig. 6, an elevation of a modified form of the invention, partly in section,

Fig. 7, a detail of parts shown in Fig. 6,

Fig. 8, another detail of parts shown in said figure,

Fig. 9 an elevation of another modification, partly in section,

Fig. 10, a horizontal section on line 10—10 of Fig. 9, and

Fig. 11, a vertical section on line 11—11 of Fig. 9.

In the drawings, reference character 20 indicates a part of the fixed head of a machine of the type in which the needle cylinder and the dial are stationary, though it will be obvious that my invention may be applied to a machine in which the cylinder and dial revolve while the cam-carriers stand still, in which case the part 20 will be a corresponding element of such a machine. Posts 21 rise from the head and at their upper ends support a yoke 22 having an oblique bearing portion for an ob-

lique or inclined annular plate 23 held in position on the bearing by a ring 24 recessed at its under side to provide a circumferential bearing and an upper bearing for the plate 23.

The rotary cam ring 25 carries posts 26, as usual, on which are mounted a yoke 27 and posts 28, the posts carrying a yoke 29. The yoke 29 supports a post 30 secured in place by setscrews 31, and a bobbin table 32 is fixed to the post in similar manner, the table bearing arms 33 provided with bobbin holders 34 for bobbins 35. The cam ring and dial cams may be caused to rotate together by some such means as are shown in the patent to Butz, 1,012,982, December 26, 1911.

The needle cylinder 36, the dial 37 and the dial cam cap 38, are, or may be, of any conventional or preferred construction. A dial post 39 passes up through the dial and the dial cap and then through a sleeve 40 rotatable in the yoke 27 in any suitable manner. The post is flattened at or near its upper end and is closely embraced by a U-shaped adjusting block 41. A nut 42 having threaded engagement with the dial post rests on the adjusting block and serves to position the dial vertically.

The sleeve 40 is bifurcated at its upper end as shown at 43 in Fig. 3 and terminates in a head 44 (Fig. 1). Screws 45 are located in the forks of the sleeve and bear at their free ends against lateral extensions of the adjusting block, whereby it will readily be seen that adjustment of the screws will turn the dial post and the dial about a vertical axis, thus serving to position the dial needles accurately between the cylinder needles. The head has a central hub providing a bearing for a circular opening in the plate, and the top of the head provides a bearing for the under side of the plate. A cap 47 is fixed to the head by a screw 48 and said cap bears on the upper face of the plate, all the bearings so far described fitting the plate closely so as to insure accurate maintenance of the dial in its position of angular adjustment.

The yarn 49 passes from the bobbin 35 through any suitable guides and down through holes or passages 50 in the plate 23. It will be seen that as the cam ring revolves the plate is forced to move with it on account of the pressure of the posts 28 against

the adjacent sides of openings in the plate. Preferably removable abutments 51 are secured to the plate by bolts or the like to receive the pressure of the posts and to position the plate accurately relatively to the posts. Though the plate revolves with the cam ring the dial is held rigidly against rotation away from its position of adjustment by the inclination of the various oblique bearing surfaces on the plate and the parts supporting it and supported thereby, thus also acting in a very positive and unvarying manner to prevent any angular movement of the dial and the parts supporting it.

In the form of the device illustrated in Figs. 6, 7 and 8 the conventional parts are, or may be, as in the form just described. The dial post 39' is, however, flattened at a point approximately midway of its length and the sleeve 40 is omitted. A clevis-shaped clamping block 53 fits closely on the flattened part of the dial post and is clamped there by a bolt 54. A nut 55 threaded on the dial post rests on the block 53 and serves for adjustment of the dial post up or down. Above the nut a horizontal plate 56 has an easy turning fit on the post. Further up the post has a shoulder on which sits a block 57 with an inclined upper face on which an inclined plate 58 has its bearing. Another block 59 on the post has a hub fitting closely in a central opening in the plate 58, this block being locked against the first by a nut 60.

The two plates 56 and 58 are provided with openings to receive the posts 61 of the bobbin supporting means and with yarn passages of suitable size and number, it being noted that four of these passages are shown in Fig. 2 for the accommodation of different yarns all as may be necessary or desirable for the work the machine is to perform. At their outer periphery the plates are supported by a floating frame comprising a main body portion 62 and removable ends 63 and 64 held in place by screws or other means. At one side the body has extensions 65 carrying opposed screws 66 bearing against opposite sides of a post 67 on the head of the machine. By adjusting the screws the position of the upper plate can be varied to provide accurate adjustment of the dial and such adjustment will be rigidly and permanently maintained, as will be obvious, with the result that the dial needles may be held accurately and permanently in place relatively to the cylinder needles.

Figs. 9 to 11 depict a highly desirable form of my invention, in which the parts are arranged and supported in a manner to relieve the dial of weight and twist in very effective manner, and so as to confine the wear to points where it can do no harm. In this form of my invention the adjusting block

68 is clamped to the dial post as in the form just described and bears a post 69. The floating frame may be generally similar to that in Fig. 6, but is held rigidly to a post 70 on the machine head by a link 71 connected at its other end to said floating frame. The upper plate or disk 72 is fixed to the posts 73, said plate resting on shoulders on the posts and being clamped in place by nuts on the threaded upper ends of the posts. The frame is thus supported by the upper disk, being held against rotation by the link 71, and the lower inclined disk 72' is rotatably supported by the frame. Each disk has as many yarn passages as may be desirable and the lower disk has openings for the posts 73 which openings may be provided with abutments as in Fig. 1 as will be obvious.

A bobbin table shaft 74 extends into the elongated hub of the plate 72 and is secured thereto by set screws 75. Below said shaft in said hub there is a dial shaft 74' which extends through blocks 76 and 77, said blocks being clamped to the dial shaft between a shoulder on the shaft and a nut at the lower end of the same. The dial shaft may thus stand still while the disk 72 rotates or may rotate while the disk stands still as the case may be. The blocks 76 and 77 provide bearings for the lower inclined disk in similar manner to the structures previously described and are provided with screws 78, 78 for positioning the dial needles relatively to the cylinder needles, as in the form first described.

As illustrated, the plate 56 in Fig. 6 may have a limited clearance at its outer periphery to permit a certain amount of side play, and the same is true of the inner peripheral bearing of plate 72' in Fig. 9, but the other plates should fit accurately at all bearing surfaces to insure correct results.

As previously stated, it will be obvious to those skilled in the art how to adapt the device of my invention for use in machines having revolving needle cylinders. Numerous modifications and adaptations of details of the device will also occur to those who understand the invention and the principles on which it is based, and therefore I do not limit myself to the specific devices shown in the drawings and described in the specification, but only as indicated in the appended claims.

Having thus fully described my said invention, what I claim and desire to secure by Letters Patent is:

1. In a knitting machine, a dial, a cylinder, a cam ring, yarn-supporting means above the dial, an inclined plate above the dial having yarn passages, and means acting through the plate for holding the dial and cylinder against rotation relative to each other, substantially as set forth.

2. In a knitting machine, a dial, a cylin-

- der, a cam ring, yarn-supporting means above the dial, an inclined plate below the yarn-supporting means, and means acting through the plate for holding the dial and cylinder against rotation relative to each other while permitting rotation of the cam ring and the plate relative to the dial and cylinder.
3. In a knitting machine, a dial, a cylinder, a cam ring, yarn-supporting means above the dial, an inclined plate below the yarn-supporting means, and connections from the head of the machine acting through the plate to prevent relative rotation between the dial and the cylinder.
4. In a knitting machine, a dial, a cylinder, a cam ring, an oblique plate contacting with oblique bearing faces on the machine fixed respectively with relation to the dial and the head of the machine, and connections between the cam ring and the plate for causing the cam ring and the plate to rotate in unison.
5. In a knitting machine, a dial, a cylinder, a cam ring, yarn-supporting means on the cam ring including upright posts, an oblique plate having openings to receive said posts, and also having yarn passages, and elements connected respectively to the dial and the head of the machine, said elements having oblique faces engaging the plate interiorly and exteriorly of said openings.
6. A device as in claim 5, with removable abutments on said plate engaging said posts.
7. A device as in claim 5, with adjusting means acting on said plate to vary the angular relation between the needles of the cylinder and the dial.
8. In a knitting machine, a dial, a cylinder, a cam ring, yarn-supporting means on the cam ring including upright posts, an oblique plate having openings to receive said posts and also having yarn passages, a dial post, elements connected to the head of the machine with oblique bearing faces engaging the upper and lower faces of the plate, a sleeve coaxial with the dial post with an oblique face engaging said plate, and means for adjusting the sleeve angularly with reference to said post.
9. In a knitting machine, a dial, a cylinder, a cam ring, yarn-supporting means on the cam ring including upright posts, an oblique plate having openings to receive said posts and also having yarn passages, a dial post, elements connected to the head of the machine with oblique bearing faces engaging faces of said plate, a sleeve coaxial with the dial post with an oblique face engaging said plate, a block non-rotatably secured to said dial post, and means for varying the angular relation of said sleeve and said block.
10. In a knitting machine, a dial, a cylinder, a cam ring, yarn-supporting means on
- the cam ring including upright posts, an oblique plate having openings to receive said posts and also having yarn passages, a dial post, elements connected to the head of the machine with oblique bearing faces engaging faces of said plate, a sleeve coaxial with said dial post with an oblique face engaging said plate, and a nut bearing on said sleeve for adjusting the dial post vertically.
11. In a knitting machine, a dial, a cylinder, a cam ring, yarn-supporting means on the cam ring, a dial post, an oblique plate having yarn passages, an oblique bearing for the plate coaxial with the dial post, and means acting on said bearing for adjusting the dial relatively to the cylinder in an angular sense.
12. In a knitting machine, a dial, a cylinder, a cam ring, yarn-supporting means above the dial, an oblique plate between the dial and the yarn-supporting means having passages for the yarns, a supporting means for said plate, connections from said supporting means to the head of the machine for holding the supporting means against rotation relatively to the head, a dial post, and connections from the dial post to said supporting means for adjusting the dial angularly with reference to the cylinder.
13. In a knitting machine, a dial, a cylinder, a cam ring, posts on the cam ring, a disk sustained by said posts, bobbin supporting means on said disk, a floating frame carried by said disk, means for holding the frame against rotation relatively to the head of the machine, an inclined plate on said frame serving to hold the dial and cylinder against relative rotation, and means for adjusting the dial angularly relatively to said inclined plate.
14. A device as in claim 13, said adjusting means including a clamp on the dial post, and a nut threaded on the dial post above said clamp whereby said clamp serves as a washer for said nut.
15. In a knitting machine, a dial, a cylinder, a dial post, a yoke carried by the cam ring, said yoke supporting the dial post, a nut threaded on the upper end of the dial post for adjusting the dial up or down, and a bifurcated block on the dial post below said nut, said post having its sides flattened for engagement by the forks of said block.
16. In a knitting machine, a dial, a cylinder, a cam ring, means for adjusting the dial vertically including a nut on the dial post, a block non-rotatably secured to the dial post, said nut resting on said block, and means coacting with said block for aligning the dial.
17. In a knitting machine, a dial, a cylinder, a cam ring, a dial post, an oblique bearing coaxial with the dial post, an inclined disk on said bearing, a floating frame

providing a peripheral bearing for said disk, a horizontal disk coaxial with the dial post and carried by said frame, and means acting on said bearing for adjusting the dial 5 angularly with reference to the cylinder.

18. In a knitting machine, a dial, a cylinder, and means for preventing relative rotation of the dial and cylinder including elements having bearing surfaces inclined at an acute angle to the axis of the machine, certain of said surfaces being non-rotatably fixed with reference to the dial and the cylinder respectively and an intermediate element being rotatable with reference to the dial and the cylinder.

19. In a knitting machine, a dial, a cyl-

inder, a cam ring, yarn-supporting means above the dial, an inclined plate above the dial having yarn passages, a stationary bearing surface for the plate, and a connection 20 from the dial to the central part of said plate.

20. In a knitting machine, a dial, a cylinder, a cam ring, a dial post, an oblique bearing coaxial with the dial post, an inclined disk on said bearing, and means rigid 25 with the cylinder for holding the inclined disk against rotation about the central axis of the machine.

In testimony whereof I affix my signature.

GEORGE D. COLLAR, JR.
